United States Patent

Des. 237,585
Patented Nov. 11, 1975

237,585

PITCHER

Frank Goertzen, 1 Oriole Road, Toronto M4V 2E7,
Ontario, Canada

Filed Mar. 28, 1974, Ser. No. 455,939

Term of patent 14 years

Int. Cl. D7—01

U.S. Cl. D7—64

FIG. 1 is a side elevational view of a pitcher showing my new design;

FIG. 2 is a top plan view of FIG. 1;

FIG. 3 is a front elevational view of FIG. 1;

FIG. 4 is a rear elevational view of FIG. 1;

FIG. 5 is a bottom plan view of FIG. 1; and

FIG. 6 is a cross sectional view taken along the line 6—6 of FIG. 1.

I claim:

The ornamental design for a pitcher, substantially as shown and described.
